UNITED STATES PATENT OFFICE.

SATTERLEE ARNOLD, OF BROOKLYN, NEW YORK, ASSIGNOR TO ANNA M. ARNOLD, OF SAME PLACE.

LINK OR PITMAN.

SPECIFICATION forming part of Letters Patent No. 311,558, dated February 3, 1885.

Application filed June 28, 1884. (No model.)

To all whom it may concern:

Be it known that I, SATTERLEE ARNOLD, a citizen of the United States, residing at Brooklyn, in the county of Kings and State 5 of New York, have invented certain new and useful Improvements in Links or Pitmen, of which the following is a specification, reference being had therein to the accompanying drawings.

10 The object of my invention is to provide a link or pitman for connecting crank-pins and similar devices, of such construction that the parts may be easily assembled together and the bearings thereof be equally fitted by one 15 adjustment, while any looseness occasioned by wear may be readily compensated for.

In the drawings, Figure 1 is an elevation of my link or pitman with crank-pins adapted thereto. Fig. 2 is a sectional view of the 20 same, and Fig. 3 represents the slotted caps in detail.

A indicates a hollow barrel or sleeve having right and left hand screw-threads on its opposite ends, an annular shoulder, *a*, adjacent to one of the threaded ends, and an internally-threaded check-nut, *a'*, fitting the other threaded end and forming an adjustable shoulder.

B is a stem fitting loosely in the barrel A, and 30 preferably having its middle part somewhat reduced in size to lessen its weight. This stem B is made of a length equal to the distance between the crank-pins or parts which are to be connected, and as the crank-pins C, 35 as herein shown, are provided with spherical heads the ends of the stem B are shown as being formed concave, so as to form bearings fitting the same.

D are caps having slots *d d* to receive 40 the shanks of the crank-pins, and internally threaded to fit the threaded ends of the barrel A. These caps, when designed to be used with spherical-headed pins, are formed concave internally at their ends, as shown, to fit 45 the same.

When it is desired to make a connection, as of the pins C, (which will first be firmly screwed into the parts for which they are designed,) the caps D will be placed over the

pins, and the barrel A, in which has been 50 placed the stem B, will then be adjusted to the caps, and by turning said barrel the caps will be drawn toward each other until the stem B fits snugly and equally against the pins C. The check-nut or adjustable shoulder *a'* 55 will then be tightened against its adjacent cap, thus preventing further rotation of the barrel and making a firm connection. The shoulder *a* and the check-nut *a'* are preferably milled exteriorly, as shown in Fig. 1, to 60 facilitate the rotation of the barrel and of the said nut.

In rotating the barrel to make the above-described adjustment of the parts it will be understood that the caps D will be prevented 65 from rotating with the barrel by the pins C passing through the slots *d* in said caps.

When it is desired to adjust the parts to take up any looseness occasioned by wear of the bearings at the ends of the stem B or of 70 the pins C, it is only necessary to loosen the check-nut or adjustable shoulder *a'*, turn the barrel to take up the looseness, and then tighten said check-nut again.

Instead of making the shoulders *a* and *a'* 75 fixed and adjustable, respectively, as above described, it will be obvious that both shoulders may be made adjustable, or, in case it is not desired to compensate for wear, both shoulders may be fixed; but the construction shown 80 is considered the best.

Having thus described my invention, I claim and desire to secure by Letters Patent—

1. A link or pitman consisting of the combination of a hollow barrel or sleeve having 85 right and left hand screw-threads at its opposite ends, a stem placed loosely in said barrel, and threaded caps fitting the threaded ends of said barrel, substantially as set forth.

2. A link or pitman consisting of the combination of a hollow barrel or sleeve having 90 right and left hand screw-threads at its opposite ends, an annular fixed shoulder adjacent to one of the threaded ends, and a check-nut or adjustable shoulder fitting the other threaded end, a stem placed loosely in said barrel, and threaded caps fitting the threaded ends of 95 said barrel, substantially as set forth.

3. The combination of the barrel A, having right and left hand threaded ends, annular shoulder a , and check-nut a' , stem B, having concave ends, pins C, having spherical heads, and caps D, having slots d , and threaded to fit the threaded ends of said barrel, substantially as set forth.

In testimony whereof I affix my signature in presence of two witnesses.

SATTERLEE ARNOLD.
